UNITED STATES PATENT OFFICE.

JEMERSON MOORE, OF OKLAHOMA, OKLAHOMA.

FRUIT PICKER.

1,415,945.

Specification of Letters Patent. Patented May 16, 1922.

Application filed February 6, 1920. Serial No. 356,735.

To all whom it may concern:

Be it known that I, JEMERSON MOORE, a citizen of the United States, residing at Oklahoma, in the county of Oklahoma and 5 State of Oklahoma, have invented certain new and useful Improvements in Fruit Pickers, of which the following is a specification, reference being had to the accompanying drawings.

10 The object of the invention is to provide a suitable device for reaching and picking fruit.

Figure 1 of the accompanying drawings is an elevation view of the device, and for 15 convenience of this description is referred to as a front elevation.

Figure 2 is an elevation view taken in the direction of the arrow 2 of Figure 1.

Figure 3 is a rear elevation showing an 20 assemblage of certain portions of the device.

Figure 4 is a front elevation showing assemblage of certain other parts.

Figure 5 is a perspective view showing 25 an optional construction of one of the parts appearing in Figure 4.

Like characters of reference designate like parts in all the figures.

The device includes a stationary rear jaw 30 6 which is annular in form and made of strong wire or rod.

This jaw 6 is mounted on the upper end 35 of a suitable square pole 7 by having the ends of its wire or rod turned downward on opposite sides of said pole as at 8 and inserted tightly into the pole as at 9; a sheet-metal holding clip 10 being hooked around the down-turned ends 8 and riveted to the extreme upper end of the pole to 40 firmly anchor the jaw in place.

A long flexible bag 11, large enough to hold as much fruit as can be conveniently handled on the pole 7, has its upper end attached to the annular jaw 6 preferably by 45 hemming the edges of said bag around the wire or rod of said jaw as shown.

An edge portion of the bag may be drawn forward through the lower part of the annular jaw 6 and tacked to the upper end of 50 the pole 7 as at 12, thus partly relieving the upper part of the jaw from the weight of the contents of the bag.

The lower end of the bag 11 may be secured to the pole 7 to prevent swinging, and

intermediate portions of the bag may also be secured to the pole if found necessary.

In further arrangement, a second and smaller jaw 13 of strong wire or rod is pivoted to the pole 7 and adapted to coact with the stationary jaw 6 in engaging the fruit. 60

The ends of the wire or rod of the coacting jaw 13 are turned straight downward as at 14 and 15 and pivoted to the pole 7, the end 14 passing pivotally through the upper tubular end 16 of a supporting plate 65 17 which is riveted to the pole, and being formed into a crank 18 for controlling the movements of the jaw, while the other end 15 is formed into an embracing eye 19 around the pivotal portion 20 of the end 14 70 between said plate 17 and crank 18.

As an optional construction, and as shown in Figure 5, the down-turned end 15 of the pivoted jaw 13 may be formed into a crank 18^b after being bent into complete 75 embrace of the pivotal portion 20 which passes through the plate 17, said pivotal portion 20 then being bent downward as at 21 merely to keep the end portions 14 and 15 of the jaw from spreading apart. 80

The pivoted jaw 13 is covered and centrally closed by flexible sheet material 22, so that when closed into or against the stationary annular jaw 6 it forms a closure for the bag 11. 85

As shown only in Figure 2, the stationary jaw 6 may be provided with a cutting blade 23, so that when the fruit 24 is caught and forced through said jaw by the jaw 13 the stem 25 of the fruit is cut by said blade 90 and allows the fruit to fall into the bag 11.

The blade 23 may be provided with integral back-turned clips 26 which partly embrace the jaw 6, and may be wired to said jaw as at 27. 95

An operating rod 28 is attached to the crank 18 of the jaw 13 and extends down along the pole 7 to within easy reach of the person using the device, the lower portion of the rod passing slidably through a 100 guiding bearing 29 on the pole.

The following is claimed:

1. In a fruit picker, an annular jaw, a polygonal pole, the said jaw having ends turned downward upon opposite sides of 105 said pole and inserted tightly in the latter, a metal clip hooked around the down-turned ends and riveted to the pole, a flex-

ible bag having its upper end secured to said jaw, with an edge portion of the bag drawn forward through the lower part of the jaw and secured to the upper end of the pole.

2. In a fruit picker, an annular jaw, a polygonal pole, the said jaw having ends turned downward upon opposite sides of said pole and inserted tightly in the latter, 10 a metal clip hooked around the down-turned ends and riveted to the pole, a flexible bag having its upper end secured to said

jaw, with an edge portion of the bag drawn forward through the lower part of the jaw and secured to the upper end of the pole, and 15 a jaw pivoted to the pole at a point below the first-named jaw and having a flexible covering and a pivotal portion mounted on the pole and having a crank portion and an eye embracing the same.

Witness my hand this 15th day of December, 1919.

JEMERSON MOORE.
